[57] **CLAIM**

The ornamental design for a hand tool for inductively testing continuity in electrical ignition systems and for removing spark plug boots, as shown and described.

DESCRIPTION

FIG. 1 is a perspective view of a hand tool for inductively testing continuity in electrical ignition systems and for removing spark plug boots embodying my new design.

FIG. 2 is a bottom plan view thereof.

FIG. 3 is a side view taken from the left of FIG. 2.
